FEEDING ATTACHMENT FOR PRINTING PRESSES

Walter D. Berry, Orangeburg, S. C., assignor of thirty-three and one-third per cent to May Whetstone Berry, Orangeburg, S. C.

Application October 27, 1934, Serial No. 750,367

11 Claims. (Cl. 101—287)

This invention is a paper feeding attachment for job printing presses and has for its object the provision of a mechanism whereby single sheets may be fed from a supply of sheets to the platen 5 and the printed sheet transferred to a delivery board or table. The invention provides vacuum-operated means for withdrawing a single sheet from a stack of sheets and delivering the same at its lower edge to grippers which carry it to the 10 platen in the printing position, the upper edge of the sheet being engaged by other grippers as the sheet travels downwardly so that it will be held smoothly upon the platen in the act of printing, the upper grippers withdrawing the printed sheet 15 and both sets of grippers being operated automatically to release the sheet at the proper time and discharge it onto the delivery board. It is also an object of the invention to provide mechanism for the stated purpose which may be easily 20 placed in position on a printing press and will support the supply of sheets on edge above the delivery board. Other objects of the invention will appear incidentally in the course of the following description, and the invention resides in 25 certain novel features which will be particularly defined in the appended claims.

In the drawings:

Figure 1 is a side elevation, partly broken away and in section, of a sheet-feeding attachment embodying the present invention.

Figure 2 is a similar view showing the parts in the position of delivering a sheet against the platen to receive an impression.

Figure 3 is an enlarged front elevation of the 35 grippers and immediately adjacent parts.

Figure 4 is a section on the line 4—4 of Figure 3.

Figure 5 is an enlarged detail section on the line 5—5 of Figure 1.

Figure 6 is a detail perspective view showing the means whereby the upper grippers are caused to release a sheet.

Figure 7 is an enlarged side elevation of the means for opening the lower grippers.

Figure 8 is a detail perspective of a lower gripper.

Figure 9 is a transverse section more particularly showing the gearing whereby the feeding mechanism is driven.

Figure 10 is a detail front elevation of the paper stack with the vacuum devices for withdrawing one sheet.

Figure 11 is a section on the line 11—11 of Figure 2.

Figure 12 is a section on the line 12—12 of Figure 2.

Figure 13 is a detail section through the connection between a driving eccentric and the lever driven thereby.

Figure 14 is a detail perspective view of some of the parts shown in Figure 11.

Figure 15 is a detail section through a valve in the suction line.

The printing press comprises a frame 1 and a 10 platen 2 pivotally mounted upon the frame to receive sheets or stock to be printed. The platen is rocked in the operation of the press through mechanism, a portion of which is indicated at 4 in Figure 1, which, in itself, constitutes no part 15 of the present invention so that detailed disclosure of the same is deemed unnecessary. The rocking of the platen is, of course, accomplished in consonance with the operation of the feeding mechanism so that the sheet which is to be printed will be placed in proper position on the platen during an interval in which the action of the feeding mechanism is reversed.

The sheet-feeding attachment comprises a frame consisting of side plates 5 and a lower bed 6 extending between the lower edges of said side plates and adapted to support a delivery table (not shown) which receives the printed sheets, this bed and frame being carried by a pedestal 7 which may be equipped with casters so

as to be easily moved to and from the printing press. The upper ends of the side plates 5 are connected and braced by a deck 8 upon which the paper sheets are stacked on edge, as shown at 9, against a follower 10, the deck being inclined, as shown clearly in Figs. 1 and 2, so that the sheets may be easily supported on edge, and the follower being moved upwardly as the sheets are removed.

At the front end of the bed or table 6 is secured a transverse rail 11 which is adapted to bear against a shoulder 12 on the upper edges of the frame of the printing press so that the sheet-feeding frame will be held against backward movement from the press. On the under side of the frame, at the rear thereof, are secured hangers 13 in which is journaled a shaft 14 carrying a gear 15 meshing with a pinion 16 on a shaft 17 which is carried by a rocking frame 18, said rocking frame 18 being pivotally hung upon the shaft 14 and the shaft 17 carrying a pinion 19 at its end remote from the pinion 16. See Figure 9. The shaft 14 is extended beyond the hanger 13 at one end and upon said end is secured a cam disc 20 having an eccentric groove 21 in its inner side, the

5

20

45

50

55

groove being defined, in the present instance, by a track member 210 secured to the disc. Working in the groove 21 is a roller 22 on the end of an arm or lever 23. When the sheet-feeding mechanism is moved into position at the feeding side of the printing press frame, the pinion 19 will mesh with a driving gear 25 which forms a part of the train of gearing for operating the platen and cooperating parts of the press, so that motion will be transmitted from said gear 25 to the pinion 19 and then through the gearing, which has just been described and is shown fully in Figure 9, to rock the arm 23.

The rocking arm or lever 23 is pivoted between its ends, as at 24, upon the adjacent side plate 5, and a link 123 connects the upper end of the rocking arm with a lever 26 which is pivotally mounted upon the side of the frame, a similar lever being mounted at the opposite side of the frame and the two levers being connected by a rock shaft or pivot rod 27, as will be understood. The levers 26 are pivoted at their front ends to the sides of a frame 28 and to the upper ends of the side members of said frame are pivoted rocking arms or auxiliary lever 29, said auxiliary levers being pivoted at their rear ends upon the side plates 5 at the rear of the same and at points above the pivot 27, as shown at 30, the levers 26 being connected and braced adjacent their front ends by a cross bar 31, shown most clearly in Figure 3. It will now be understood that as the gearing rotates, the disc 20 will impart an oscillatory motion to the arm 23 and through the link 123 to the connected levers 26 so that the frame 28 will be moved from the position shown in Figure 1 to the position shown in Figure 2 and then back to the initial position. During this reciprocation of the frame 28, the rocking arms 29 will also cause the frame to rock upon its pivotal connections with the levers 26 so that, while in its upper position the frame is nearly vertical, in its lower position it will be inclined somewhat more and will correspond with the position of the platen of the press.

Pivoted to one of the rocking arms 29 adjacent the fulcrum of the same, as shown in Figures 1 and 2, is a link 131 which has its upper end pivoted to the rearwardly extending arm of an angle lever 32 which is fulcrumed upon the side of the frame 5 and has the end of its upwardly extending arm pivoted to the rear end of a connecting rod 33 which extends forwardly and is pivoted on a rod 34 which extends across the front of the stack of paper sheets and is provided with arms 35 journaled at their lower ends upon the deck 8, at the sides of the same, and of the same length as the upper arm of the angle lever 32 whereby the angle lever, the arms 35, the connecting rod 33, and the deck will form a parallelogram. Mounted upon the carrier rod 34 are suction cups 36 which will move to and from the stack of paper sheets as the machine is operated whereby the suction will cause the outside or front sheet of the stack to move forwardly with the cups into a position at the edge of the deck where it will be clasped by the lower grippers. The vacuum cups 36 are to be connected with any vacuum apparatus which may be conveniently located and which is not illustrated in the accompanying drawings inasmuch as in itself it forms no part of the present invention, hose or flexible pipes, indicated at 37, being attached to the vacuum cups and leading therefrom to the vacuum apparatus, as will be understood.

In Figure 2 the cups are shown as resting against

the stack of paper sheets, while in Figure 1 they are shown as having carried one sheet from the stack into the position where it is engaged by the lower grippers.

As shown most clearly in Figure 3, the frame 28 is substantially U-shaped and upon the base of the frame is formed or secured a plate or upstanding flange 38 against which the lower edge of the sheet to be printed is clamped in the operation of the device. In the base or cross member of the frame 28 at intervals are slots or a groove 39, shown most clearly in Figures 7 and 8, in which are engaged teeth or spurs 40 formed at the ends of clips 41, the arms of which are disposed respectively above and below the base of the frame 28, as shown most clearly in Figures 4, 7 and 8. The clips may be provided in such numbers and at such intervals as may be deemed most desirable. Rising from the clips at one side of the base-engaging members thereof are resilient fingers 42 which are curved or bent toward the plate 38 and adapted at their upper extremities to bear against said plate, as shown in Figure 4. Disposed between the gripping fingers 42 and the gripping plate 38, is a transverse bar 43 which is connected with the base of the frame by hinges 44 and is provided at one end with an angularly disposed surface constituting a cam, as shown at 45. Pivoted in brackets 46 at the lower corners of the frame 28 are side members of a frame 47, the upper ends of said side members being connected by a cross rod 48, as clearly shown. One of said side members 47 has a laterally extending arm 49 adjacent its pivot equipped with a roller 50 which is adapted to ride upon a curved track 51 extending from the frame 5 at one side of the platen, as shown in Figures 1 and 2, it being noted that the lower end of this track is doubled upon itself to provide a shoulder 52. Pivoted upon the upper or forward end of the arm 49 is a dog or trigger 53 which is adapted to ride against the cam surface 45 and thereby rock the transverse bar 43 so as to force the gripping fingers 42 away from the gripping plate 38, as shown in Figure 7. The trigger bears against a stop 54 formed on the arm and is held to said stop by a leaf spring 55 carried by the arm and bearing against the rear edge of the trigger. A retractile spring 56 is attached at one end to the frame 28 adjacent the lower end of the same and at its opposite end is attached to the cross bar 48 so that said cross bar and the ends of the side arms 47 are held yieldably in the position shown in Figure 2. In the position shown in Figure 2, the sheet to be printed is held by and between the upper and lower grippers and the roller 50 is bearing against the shoulder 52 at the lower end of the track 51. As the feeding frame is swung upwardly to the position shown in Figure 1, the arm 59 will be rocked slightly by the engagement of the roller 50 with the end of the track and it will be held in this slightly rocked position as long as the roller is traveling on the track. When the side members 47 are thus rocked about their pivotal connections with the frame 28, the dog or trigger 53 is caused to ride on the cam surface 45 and push the bar away from the gripping plate 38 so that the gripping fingers 42 will be moved away from said plate and the lower edge of the printed sheet will be released. The resiliency of the fingers 42 will exert a tension upon the trigger which will hold the parts in the position shown in full lines in Figure 7, and as the frame 28 approaches the upper limit of its movement, projections 57 on the side pieces 47 at the ends of

the cross bar 48 will engage and ride in downwardly inclined grooves 58 in the inner faces of the side plates 5 so that the said members 47 will be swung downwardly and the arm 49 will be rocked to the position shown in dotted lines in Figure 7, thereby releasing the bar 43. Just before the trigger 53 is released from the cam surface 45 by this additional rocking of the arm 49, the vacuum cups will have brought a sheet into the position shown at 59 in Figure 1, so that the edge of the sheet will drop into position between the clamping plate 38 and the gripping fingers 42. As the parts assume the position shown in dotted lines in Figure 7, the trigger is released from the cam 45 and the gripping fingers 42 then move against the lower edge of the sheet under their own resiliency so that the sheet will be grasped and held by the fingers and the gripping plate. The spring 56 will be put under tension by this action so that as the side members 47 clear the grooves 58 on the return stroke, the rocking arms will be returned to the position shown in full lines in Figure 7, and then to the position shown in Figures 1 and 2. On this return movement, however, the trigger 53 will ride past the cam surface 45 and resume its original position under the same so as to again actuate said surface and the bar 43 in the next cycle of operations. The spring 55 will yield to this return movement of the trigger so that it will ride easily past the bar 43 which will be carried to its position against the gripping plate by the action of the gripping fingers.

Extending upwardly from the cross bar 48 are supporting plates or brackets 59 which have longitudinal slots 60 therein and upon which, adjacent their free ends, are pivoted the upper members of lazy tongs 61 which extend downwardly and are pivoted at their lower extremities to a cross bar or plate 62 which constitutes the gripping board or plate of the upper grippers. At the center of each lazy tong, a bolt 63 is engaged through the corresponding slot 60, and a wing nut 64, mounted on the front end of the bolt, is adapted to be turned home against the adjacent members of the lazy tongs so as to secure them in a set position. These lazy tongs form a convenient and easily operated means for adjusting the upper grippers toward or from the lower grippers so as to set the device for a sheet of any desired size. Connected with the gripping plate 62 by hinges 65 is a flat-sided bar 66 having gripping fingers 67 projecting from its lower edge at intervals, and secured upon the gripping plate 62 at the ends thereof are leaf springs 68 having their free ends bearing upon said bar 66 so as to hold the same in either the open or the closed position. A stop lug 69 is provided on the gripping plate 62 adjacent the bar 66 so that when the bar is turned to the open position, it will rest against said stop and, consequently, its opening movement will be limited and it cannot be swung so far that it will fail to engage the sheet. At one end of the bar 66 is a crank 70 terminating in a stud 71 which is adapted to ride against the eccentric edge 72 of a trip bar 73 which is secured upon the side plate 5 in proper position to be engaged by said stud as the side members 47 assume the position shown in Figure 1. The gripping fingers 67 will be thereby swung to the open position shown in Figure 5 so that a sheet of paper may be received between them and the gripping bar or plate 62. As the feeding frame moves downwardly the sheet, shown at 59, will be drawn downwardly with it

and the frame members 47 will be swung toward the position shown in Figure 4 to bring the gripping fingers above the upper edge of the paper sheet whereupon the crank stud 71 will ride against a trip lug 74 on the adjacent side member of the frame 28 to rock the gripping fingers into the closed position shown in Figures 3 and 6, thereby gripping the upper edge of the paper sheet. The cycle of operations is then repeated until all of the paper has been printed or the job has been completed.

The hose or pipe 37 extends from the suction cups to a vacuum apparatus of any preferred form and mounted upon the frame of the sheet-feeding apparatus is a valve casing 80 inserted 15 in the suction line, as shown most clearly in Figure 15. A piston valve 81 is fitted in a branch of the valve casing and a port 82 in a partition 83 of the casing exposes the piston to the force of the suction, the valve stem 84 depending from 20 the piston through a guide 85 on the adjacent side plate 5. The lower end of the valve stem is arranged over the inner end of a latch 86 which is pivoted between its ends upon a bracket 87 extending laterally from the side plate 5, the outer 25 end of the latch seating in a notch 88 in the upper end of a trip lever 89 which is pivoted at its lower end upon the bracket 87, as clearly shown. The lever 89 has a hub member 90 which is keyed to the pivot rod 27 and loose upon said 30 rod is an outer hub member 91 from the outer end of which rises a crank or lever 92, the upper end of said crank or lever being pivoted to a bar or rod 93 which carries a cap 94 at its free 35 end adapted to fit over the upper end of the impression throw-off lever 95 of the press. In the outer end of the hub 90 is a radial slot 96 and in the inner end of the hub 91 is a similar slot 97 adapted to aline with the slot 96, a longitudinal recess 98 extending from the slot 97 toward the outer end of the hub 91. A trigger 99 is slidably mounted in the hub 91 in the slot 97 and has a tongue 100 fitting in the recess 98 and bearing upon an expansion spring 101 housed in the recess. The trigger 99 projects radially beyond the hubs and bears against the lever 89, normally seating in a notch 102 therein. A retractile spring 103 is attached to the lever 89 and to the bracket 87 and tends constantly to rock the lever toward the frame, this movement being 40 resisted by the latch 86. Projecting laterally from the lever 89 is a stud 104 which may be engaged at times by a cam lug 105 on the outer side of the disc 20, a roller 106 being provided on the stud to reduce frictional wear and resistance. 45

As long as the apparatus is operating properly, the suction will hold the valve in its raised position, and the trigger 99 will be held in the position shown in Figure 11, the hub 90 rotating and the hub 91 remaining at rest while the lug 105 will 50 clear the roller 106 and stud 104. Should the suction cups, however, fail to work, for any reason, the vacuum will be broken and the valve stem will drop onto the latch 86 and rock the same, as shown by the dotted lines in Figure 12, 55 to release the lever 89 which will thereupon be rocked out of engagement with the trigger 99 under the influence of the spring 103. The trigger is immediately pushed into the slot 96 by the spring 101, thereby locking the two hubs together 70 so that the lever 92 and rod 93 will be actuated to rock the impression throw-off lever 95 with the usual result. The rotation of the cam disc 20 will then bring the lug 105 into engagement with the roller 106 for resetting the parts and 75

normal operation will be resumed when the vacuum has been restored.

To disconnect the feeding apparatus from the impression throw-off lever, it is necessary to merely lift the cap 94 from the lever.

From the foregoing description, taken in connection with the accompanying drawings, it will be seen that I have provided a sheet-feeding mechanism which may be readily placed in operative relation to a printing press and which will be operated in consonance with the press to feed a sheet to the printing position and then withdraw the sheet. It will also be noted that while the sheet is in the printing position it is held at both its upper and its lower edges so that it will be smooth upon the platen and will not be apt to have a blurred impression. The sheet is properly centered without the use of gage pins which are eliminated and rendered unnecessary.

Having thus described the invention, what is claimed as new is:

1. Sheet-feeding mechanism for a printing press comprising a frame having an upper inclined deck upon which sheets may be stacked on edge and a lower bed upon which the printed sheets may be delivered, means to withdraw a single sheet from the stack, means to grip the lower edge of the withdrawn sheet and carry the same to printing position, means for gripping the upper edge of the sheet as it moves to printing position, the lower gripping means being released as the sheet is withdrawn from printing position and the upper gripping means being released as the sheet assumes a position above the delivery bed, and an oscillatory frame supporting said second and third mentioned means.

2. A sheet-feeding mechanism for a printing press comprising a frame having an upper deck upon which paper sheets may be stacked on edge and a lower delivery table, vacuum cups movable toward and from the stack of sheets to remove the front sheet therefrom, means for creating a vacuum in the cups, gripping mechanism automatically movable in consonance with the means and vacuum cups to grip the edges of the removed sheet and carry the same to and from printing position and release it as it is withdrawn from printing position to a delivery position below the deck, and an oscillatory frame supporting the gripping mechanism.

3. In a sheet-feeding means for a printing press, an oscillatory frame, means for moving said frame to and from printing position, means for supporting a stack of paper sheets at a point above said frame, means on the frame for withdrawing a sheet from said stack, and upper and lower gripping members on the oscillatory frame to engage the upper and lower edges of a sheet as the frame moves to and from printing position.

4. In a sheet-feeding mechanism for a printing press, an oscillatory frame movable to and from printing position, lower grippers mounted on the frame, upper grippers carried by the frame, means mounted on the frame to open the lower grippers as the frame moves upwardly and close the same upon a sheet as the frame starts its downward movement, and means for opening the upper grippers as the frame stops its upward travel and close said grippers as the frame starts its downward travel, said last mentioned means comprising a cooperating crank stud and trip lug.

5. A sheet-feeding mechanism for a printing

press comprising a frame adapted to be engaged with a printing press, means on the upper portion of said frame to support a stack of paper sheets, means on the lower portion of said frame to receive printed sheets, an oscillatory frame, means mounted on the first-mentioned frame and driven from the power of the printing press for shifting said oscillatory frame to and from printing position, means for separating a sheet of paper from the stack, lower grippers on the oscillatory frame to engage the lower edge of a separated sheet as said frame moves to printing position, means on said frame for gripping the upper edge of the sheet as the frame moves toward printing position, and means for releasing the printed sheet as said frame moves toward delivery position.

6. A sheet-feeding mechanism for a printing press comprising an oscillatory frame movable to and from printing position, lower grippers carried by said frame, upper grippers adjustably mounted on said frame, and means for opening and closing said grippers during travel of the frame.

7. Sheet-feeding mechanism for a printing press comprising a frame, means for moving said frame to and from printing position, lower grippers mounted upon the frame, supporting arms extending from the upper portion of the frame, lazy tongs mounted on said arms, and upper grippers carried by the lazy tongs.

8. In a sheet-feeding mechanism, a frame movable to and from printing position, a gripping plate on said frame, resilient gripping fingers adjustably secured on the frame to cooperate with said gripping plate, a release bar disposed between the gripping plate and the fingers to release the fingers from the plate, an arm pivotally mounted upon the frame, said release bar having a cam at one end, a trigger carried by said pivoted arm and arranged to engage the cam on the release bar whereby to open the gripping fingers, and means for releasing the trigger from said cam whereby the gripping fingers may grip a sheet against the gripping plate.

9. In a sheet-feeding mechanism, an oscillatory frame movable to and from printing position, a gripping plate carried by the lower end of said frame, resilient gripping fingers mounted on the frame to cooperate with said plate, a rocking frame pivotally mounted on the first-mentioned frame at the lower corners of the same, an arm on said rocking frame, a trigger carried by said arm, means whereby the trigger will release the gripping fingers as the oscillatory frame moves upwardly, and means for rocking the rocking frame as the oscillatory frame reaches the upper limit of its movement whereby to release the trigger and permit the gripping fingers to engage a sheet.

10. A sheet-feeding mechanism comprising a frame movable to and from printing position, a rocking frame mounted on the oscillatory frame, lower grippers carried by the oscillatory frame, upper grippers adjustably mounted on the rocking frame and including a gripping plate, a rocking bar hinged upon said gripping plate and having gripping fingers extending from one side, a stop to limit the opening movement of said bar, means for holding the bar in open or closed position, a crank at one end of said bar, a cam disposed in the path of said crank whereby to rock the bar to open position as the oscillatory frame reaches the upper limit of its travel.

movement, and means on the rocking frame to engage said crank and rock the bar to closed position as the oscillatory frame begins its downward movement.

5 11. Sheet-feeding mechanism for a printing press comprising an oscillatory frame, sheet-gripping means on said frame, a normally constantly rotating hub, operative connections between said hub and said frame, a normally sta-

tionary hub, operative connections between the stationary hub and the impression throw-off lever of the printing press, a trigger mounted in the stationary hub, a trip-lever engaging the trigger, means whereby the trigger will lock the hubs together upon release of the trip-lever, and means for resetting the trip-lever and the trigger.

WALTER D. BERRY.
